UNITED STATES PATENT OFFICE.

RODRIGUE JOSEPH ANTOINE TRIANA, ANDRÉ ELIE LAURENT TRIANA, AND JUAN ORTIZ ESCOFET, OF PARIS, FRANCE.

DESIGN FOR A MOTION-PICTURE-PROJECTING CABINET.

Application filed July 11, 1925. Serial No. 14,061. Term of patent 3½ years.

To all whom it may concern:

Be it known that we, RODRIGUE JOSEPH ANTOINE TRIANA, ANDRÉ ELIE LAURENT TRIANA, and JUAN ORTIZ ESCOFET, the two former citizens of the French Republic, the latter a subject of the King of Spain, and residents of Paris, France, have invented a new, original, and ornamental Design for a Motion-Picture-Projecting Cabinet, of which the following is a specification, reference being had to the accompanying drawing, forming part thereof.

The figures are respectively a front and a side view of the motion picture projecting cabinet, showing our new design.

We claim:

The ornamental design for a motion picture projecting cabinet as shown.

In testimony whereof we affix our signatures.

RODRIGUE JOSEPH ANTOINE TRIANA.
ANDRÉ ELIE LAURENT TRIANA.
JUAN ORTIZ ESCOFET.
